PRINTING PLATE PROCESSING MACHINE

Hugh T. Greenlee, Gates Mills, Ohio, and Wesley W. Miller, Wyncote, and Gerold Litschi, Lansdale, Pa., assignors to W. R. Grace & Co., New York, N.Y.

Filed Aug. 21, 1970, Ser. No. 24,640

Term of patent 14 years

Int. Cl. D18—02

U.S. Cl. D55—1

7-1451

FIG. 1

Des. 222,685

PAGE 2

FIG. 2

FIG. 3

Des. 222,685

PAGE 5

FIG. 4

FIG. 5

FIG. 6

FIG. 1 is a perspective view of a printing plate processing machine embodying our new design;

FIG. 2 is a front elevational view thereof;

FIG. 3 is a right-side elevational view thereof;

FIG. 4 is a rear elevational view thereof;

FIG. 5 is a left-side elevational view thereof; and

FIG. 6 is a top plan view thereof.

We claim:

The ornamental design for a printing plate processing machine, as shown.
